ANGULATED SPUR

Carl A. Nafzger, Clarksville, Tex., assignor of one-half to
Walter P. Bignault, Porterville, Calif.

Filed Oct. 21, 1966, Ser. No. 4,374

Term of patent 14 years

(Cl. D30—31)

FIG. 1 is a top plan view of an angulated spur showing my new design.

FIG. 2 is an elevational view of one side thereof.

FIG. 3 is an elevational view of the opposite side from the side shown in FIG. 2.

FIG. 4 is a bottom plan view thereof.

FIG. 5 is a front elevation thereof.

FIG. 6 is a rear elevation thereof.

FIG. 7 is a perspective thereof.

I claim:

The ornamental design for an angulated spur, as shown.
